UNITED STATES PATENT OFFICE.

ALFRED J. KULL, OF FAR HILLS, NEW JERSEY.

DESIGN FOR A PAPER-WEIGHT.

45,425.

Specification for Design.

Patented Mar. 17, 1914.

Application filed January 7, 1914. Serial No. 810,886. Term of patent 7 years.

To all whom it may concern:

Be it known that I, ALFRED J. KULL, a citizen of the United States, residing at Far Hills, in the county of Somerset and State of New Jersey, have invented a new and original and ornamental Design for a Paper-Weight, of which the following is a specification, reference being had to the accompanying drawing, forming a part thereof.

The figure in the drawing is a plan view of a paperweight showing my design.

I claim:

The ornamental design for a paperweight as shown.

ALFRED J. KULL.

Witnesses:

PETER D. LANE,
W.M. H. SUETER.
